Ralph W. Brown.

ATTORNEY.

UNITED STATES PATENT OFFICE

EDWIN L. POHL, OF HARTFORD, WISCONSIN

CLOSURE FOR COLLAPSIBLE TUBES

Application filed February 17, 1927. Serial No. 168,889.

This invention relates to closures for collapsible tubes which are in common use for containing and dispensing toilet creams, pastes, artists' paints, salves and the like.

5 The types of such containers now most prevalent in use are provided with a threaded nipple and a threaded cap or closure which is wholly removable from the container. The particular disadvantage to this type of closure is the ever prevalent danger of loss or 10 misplacement of the cap thus leaving the contents of the tube open to dust laden air which in many instances renders the paste, paint, or cream unfit for further use.

15 In an endeavor to eliminate the foregoing difficulty numerous attempts have been made to anchor the closure cap to the tube, and all have terminated in the addition of lugs to the body of the tube, specially designed caps and 20 wire connections between the two elements. In every instance the complications accompanying the anchoring of the closure cap have proven costly, cumbersome or wholly impracticable when they have been subjected to 25 any extended use.

The primary object of this invention is to provide a closure for collapsible tubes which may readily be removed from its sealing position on the tube to permit the dispensing of 30 the contents thereof, and yet remain fixed to the tube to insure against its loss or misplacement.

A further object lies in the novel construction whereby the necessity of a threaded 35 nipple and closure have been eliminated and also the sliding engagement between the closure and retaining means which was subjected to considerable strain and found lacking where a wire retaining means was heretofore 40 used.

A further object is the simplicity of the present invention and the exceedingly low cost of manufacture, obtained by the elimination of elements such as threads, special anchoring means and sliding connections which have hitherto been deemed essential.

Other objects and advantages will be obvious from the following description of an illustrative embodiment of the present invention.

In the drawings:

Figure 1 is an elevational view of a collapsible tube provided with a closure of the present invention.

Fig. 2 is an enlarged side elevational view 55 of a portion of the tube.

Fig. 3 is a sectional view taken on the line 3-3 of Figure 2.

Fig. 4 is an elevational view of the closure 60 with the retaining wire shown in its normal position before being attached to the neck of the tube.

In an illustrative embodiment of the present invention a collapsible tube 1 is provided with a neck portion 2 adapted to be received in a socket 3 of a closure cap 4. A suitable insert 5 of cork or similar material is positioned in the socket 3 and serves as a seal for a mouth 6 of the tube. The closure 4 is provided with an enlarged head 7 which may be knurled or suitably shaped to offer an effective means for lifting the closure to permit its ready replacement on the tube. An annular groove 8 is provided beneath the head 7 of the closure. A retaining means such as a wire 9 is positioned in the groove 8 and bent upon itself to effect a permanent attachment of said retaining means to the closure. The retaining wire 9 is then deformed into a pair of resilient depending arms 10 whose extremities 11 may be inserted into suitable sockets 12 in the neck portion 2 of the tube. 75

The retaining means such as a wire having resilient portions is fixed to the closure as above described and the resilient depending arms will normally lie in the position as indicated in Figure 4 of the drawing. It will readily be seen that in order to position the closure onto the neck portion of the tube it will be necessary to spread the extremities of the bowed arms to permit their insertion into the sockets of the neck portion. Hence when they are so positioned there will be an inherent tendency for the flexed portions to exert a downward pressure on the closure and thus impart a pressure through the medium of the insert 5 to effect a positive seal on the mouth of the tube. 80

To relieve this tendency and remove the closure from the tube to permit dispensing

of the contents thereof, it becomes necessary only to grasp the tube in the usual manner applying the thumb to one of the resilient bowed arms and the index finger to the other bowed arms. By exerting a slight pressure on these two arms they will be deformed in such a manner as to effect a rising movement of the closure, said rising movement of the closure being sufficient to disengage the neck 10 2 of the tube from the socketed portion 3 of the closure, at which time it will be necessary only to swing the closure about the axis formed by the ends of the bowed arms 11 in the sockets 12 of the neck to displace it a 15 sufficient amount to permit dispensing of the contents of the tube without interference with the closure.

To replace the cap, after a suitable amount of the contents of the tube have been discharged, it becomes necessary only to grasp the enlarged portion 7 of the closure 4 and exert a slight pull on the same to again deform the resilient arms 10 in order to permit the closure to be swung into a vertical 25 position over the mouth 6 of the tube. When the closure is in this position, by releasing one's hold on it, the resilient arms 10 will force the closure onto the neck portion of the tube, thus insuring sealing of the mouth 6 by 30 the inset 5 in the socket 3 of the cover portion.

It will readily be seen from the foregoing description that a closure for collapsible tubes has been provided in an inexpensive and serviceable manner. There being only 35 one portion, namely, the resilient retaining means in addition to the elements normally required for containers of this type. In addition to accomplishing the desired end the cost of manufacture of the article described 40 in the foregoing specification has been greatly reduced and a material saving has been accomplished by the elimination of threads on the neck portion of the tube and the closure, together with the elimination of 45 special anchoring means which have hitherto been deemed essential in prior attempts to accomplish the same end as recited in the foregoing specification.

It will also be seen that the closure herein 50 described lends itself readily to the use to which articles of this class are subjected; namely, the frequent removal and repositioning of the closure upon the tube, as there are no elements which will become permanently 55 deformed by frequent use nor is there any possibility of loss or misplacement of the closure as it is constantly fixed to the neck of the tube by means of the resilient arms.

The ease of manipulation, the low cost of 60 manufacture, and the simplicity of the device all lend themselves to the accomplishment of the desired end, namely, the provision of a closure for collapsible tubes which may readily be removed from its sealing position 65 without removal of the same from the tube.

While the application of a closure for collapsible tubes has been described in considerable detail in the foregoing specification, it will be understood that changes may be made in the construction of the same within the limits hereinafter claimed, without departing 70 from the spirit of the invention.

I claim:

1. A collapsible container having an apertured discharge neck, a cap cooperating therewith to close the same, and a pair of resilient links connecting said container and cap and normally applying a closing pressure between said cap and neck, said links being outwardly bowed and deformable under lateral pressure to lift said cap from said neck. 75

2. A collapsible container having an apertured discharge neck, a cap cooperating therewith to close the same, and a pair of resilient links pivoted on said container and attached to said cap and normally operable to exert a closing pressure between said cap and neck, said links being outwardly bowed and deformable under lateral pressure to 80 lift said cap from said neck. 85

In witness whereof, I hereunto subscribe my name this 15th day of February, 1927.

EDWIN L. POHL.
